CLAIM

The ornamental design for a connecting device for wireless communications, as shown and described.

DESCRIPTION

FIG. 1 is a front perspective view of a connecting device for wireless communications, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines immediately adjacent the shaded areas represent the bounds of the claimed design while all other broken lines are directed to environment and are for illustrative purposes only; the broken lines form no part of the claimed design. In addition, the unshaded surface between the solid line edge and broken line in FIG. 3 forms no part of the claimed design.
